UNITED STATES PATENT OFFICE.

FERDINAND G. HENRY, OF NEW YORK, N. Y.

INTERNAL-COMBUSTION ENGINE.

1,253,969.

Specification of Letters Patent. Patented Jan. 15, 1918.

Application filed March 16, 1915. Serial No. 14,865.

To all whom it may concern:

Be it known that I, FERDINAND G. HENRY, a citizen of the United States, residing at New York, in the county of New York and State of New York, have invented certain new and useful Improvements in Internal-Combustion Engines; and I do hereby declare the following to be a full, clear, and exact description of the invention, such as will enable others skilled in the art to which it appertains to make and use the same.

This invention relates to internal combustion engines and has for an object to provide an engine embodying the features of a turbine engine and an oscillating engine operating upon the same driven shaft and from the same motive fluid.

A further object of the invention is to provide a plurality of cylinders having oscillators mounted therein and means for igniting a gaseous mixture within such cylinders to oscillate the oscillators and with means for conducting the exploded gases from such cylinders into and to act upon a turbine structure of substantially the usual and ordinary type.

A further object of the invention is to provide a plurality of cylinders having oscillators mounted therein and means for igniting a gaseous fuel within such cylinders being mounted upon an integral or connected structure and to rotate bodily about the central shaft so that said cylinders rotating rapidly through the atmosphere are cooled by contact with such atmosphere.

A further object of the invention is to provide improved means for controlling the ignition of the gases within the several cylinders as exigencies of operation may make necessary or desirable.

A further object of the invention is to provide improved means for carrying into effect the several hereinbefore recited objects.

With these and other objects in view the invention comprises certain novel constructions, combinations and arrangement of parts as will be hereinafter more fully described and claimed.

In the drawings:

Figure 1 is a view of the engine taken generally upon a longitudinal diametrical plane except where other planes are clearly indicated.

Fig. 2 is a view of the crank mechanism

in end elevation with one of the cylinders in transverse section as indicated by line 2—2 of Fig. 1.

Fig. 3 is a view taken on a plurality of planes, each of the several cylinders indicating the structure taken on a plane as for instance plane 3, 3^a, 3^b, and 3^c of Fig. 1.

Fig. 4 is a view of the engine in end elevation as indicated by arrow 4 at Fig. 1.

Fig. 5 is a detail sectional view of the passage forming communication between the exhaust from the oscillating engine to the turbine engine.

Fig. 6 is a transverse sectional view taken on line 6—6 of Fig. 5.

Fig. 7 is a sectional view taken on line 7—7 of Fig. 5.

Fig. 8 is a sectional view taken on line 8—8 of Fig. 1 and showing the position line of Fig. 6.

Figs. 9 to 13 inclusive are diagrammatic views showing the several positions of the oscillators during one complete revolution of the engine.

Like characters of reference designate corresponding parts throughout the several views.

The improved engine which forms the subject matter of this application comprises an inner and relatively fixed structure and an outer and relatively rotary structure. The fixed structure, as more particularly explained below and as perhaps best seen in Fig. 1, includes a shaft 40 and its sleeve 41, a disk 42 at its front end, a wrist pin 43 projecting forward from the disk and out of alinement with said shaft, a stationary part 44 inclosing the wrist pin, and the frame 75; and at the rear of the engine the fixed structure includes the stationary part 44' and the inner wall 35 of the turbine, both carried by the frame 75. The rotary structure consists of a body 1 and front and rear heads. The front head includes a disk 2, a drum 3 forward of the disk, and a reduced hub 4 journalized upon the stationary part 44, while the rear head includes a disk 5 and the shell 6 of a turbine. The body 1 of this rotary structure is itself made up of a plurality of similar cylinders 10 of any approved number, here shown as four and disposed between and secured to the disks of the rotary structure preferably by bolting or casting integral, although the manner of uniting is wholly immaterial to the present invention.

invention. Centrally through each of the cylinders 10 extends a shaft 11 having bearings in the cylinder heads and also a reduced bearing 12 at the exhaust end and an auxiliary bearing 13 at the crank end. Upon the shaft 11 a sleeve 14 is mounted rigidly secured to the shaft in any approved manner as by the key 15. The sleeve 14 carries oscillator blades 16 with packing of substantially the usual and ordinary type to make such blades steam-tight within the cylinders. No particular novelty is claimed for the packing.

Within the cylinders 10 stationary abutments 17 are erected against or adjacent to which the oscillator blades move in their oscillation upon the shaft 11.

The cylinder heads are provided with ports 18 and 19 which, as will be noted especially from Figs. 9 to 13 inclusive, communicate with the cylinders between the abutments 17 and the oscillators 16 and upon opposite sides of such abutments and oscillators. It will be noted that whatever the position of the oscillator but one of the ports 18 or 19 communicates with the space between the abutment and the oscillator, the cylinder being divided by the abutment and the oscillator into four chambers varying in size as the oscillator moves.

At 3^a at Fig. 3 will be seen one of the cylinder heads and at 3^b the valve 20 which rotates in engagement with such cylinder head, the said valve being shown also in side elevation and diametrical section at Fig. 1. The valve rotates about a sleeve 21 which sleeve embraces the inlet passage 22 and is provided with cut-out portions 23 which communicate with ports 24 spaced to register with the ports 18 in the cylinder head and to form the inlets of the cylinders upon opposite sides of the oscillators simultaneously. Such cut-outs 23 also communicate at other times with the ports 25 which are spaced to register with the ports 19 to form inlet ports for the opposite sides of the oscillators.

The valve 20 is also provided with ports 26 likewise spaced to register with the ports 18 of the cylinder head and other ports 27 spaced to register with the ports 19 of the cylinder head and to act as exhaust ports, both the said ports 26 and 27 communicating with the passage 28 which opens through a nozzle 29 into the shell 6 of the turbine 30, exhaust from such turbine being into the annular chamber 31 and out through the exhaust passage 32. The explosive gases are introduced to the passage 22 through the pipe 33 into an annular passage 34, the pipe 33 being carried in the stationary part 44' and the annular passage 34 surrounding the power shaft 36.

To actuate the valves 20 the said valves are provided with gears 37 which engage

intermediate idlers 38, the latter in turn engaging a pinion 39 carried upon the stationary shaft 40 which extends through the sleeve 41 and is rigidly connected with the stationary disk 42. The shaft 40 is mounted at one end in one head of the rotary structure, and at the opposite end the other head thereof rotates about the stationary disk 42, ball-bearings 48' being provided for that purpose. The disk 42 is provided with a tubular wrist-pin 43 which extends through the stationary part 44 of the structure with a shaft 45 passing through such hollow wrist-pin. The wrist-pin 43 serves to connect the rotating part with the stationary part by a plurality of links 46 pivoted thereto and in turn pivoted to cranks 47 rigidly secured upon the shafts 11 and oscillating with the oscillators 16. As the oscillators are oscillated by the explosion of the gases within their respective chambers in the cylinders it will be apparent that the tendency is to communicate the motion to rotate the disk 42 but as the disk 42 is held stationary against rotation by the wrist-pin 43 extending through the stationary member 44 the result is the rotation of the cylinders themselves carrying the oscillators therewith and the valve structures so that the gears 37 receive motion by traveling in planetary order about the pinion 39.

Antifriction bearings 48 are provided at proper points to permit the outer structure to rotate about the fixed parts of the inner structure and packing is provided at various points for the purpose of preventing leakage of the gases, all in the usual and well known manner. Power is taken off from the device from the shaft 36 or if desired by applying a belt directly to the surface of the drum 3.

The chambers upon the opposite sides of the oscillators within the cylinders are in communication by means of passages 50 and 51 which extend through the sleeves 14 and through the shafts 11. Explosion is provided in the cylinders by means of a plurality of spark plugs 52 and 53, preferably four in each cylinder as indicated at Fig. 2. The spark plugs are connected with a source of electrical energy shown at Fig. 2 conventionally at 54 and by rings 55 surrounding reduced portions of the valve 20 as shown more particularly at the lower half of Fig. 1. The rings 55 are provided with gears 56 which engage idlers 57 mounted co-axially with the idlers 38 which latter engage a pinion 58 carried rigidly upon the sleeve 41. The sleeve 41 is rigidly connected with the gear 59 which is engaged by a pinion 60 carried upon the shaft 45 which in turn carries the lever 61. It will be apparent that by moving the lever 61 through the medium of the shaft 45, pinion 60, gear 59, sleeve 41, gear 58 and idlers 57 the gears 56 carry-

ing the rings 55 may have their relation to the gears 37 changed. The rings 55 carry each a knob 62 positioned to at predetermined intervals engage one of the fingers 63 or 64 upon the levers 65 or 66. The levers 65 and 66 respectively carry switches 67 and 68 adapted to complete the circuit from the source of energy 54 respectively to the spark plugs 53 and 52. As the ring 55 rotates therefore, the knob 62 alternately causes the completion of the circuit to the plugs 53 and 52 to cause sparks in their respective chambers to ignite the gaseous contents therein. The movement of the ring 55 relative to the valve 20, therefore, advances or retards the spark in the usual well known manner and for the usual well known reason.

In operation an explosive mixture is introduced through the pipe 33 and passage 34 to the inlet passages 22 where it passes through one of the passages 24 and ports 18 into the cylinder in the position shown at Fig. 9. The rotation of the engine causes the oscillator to move to the position shown at Fig. 10 thereby drawing in a charge of gas through the ports 18. At this point the valve 20 in its continued rotation closes ports 18 and the reverse movement of the oscillator compresses the gas in the space as shown at Fig. 11. Coincidentally the valve 20 has moved so that the passages 27 register with the ports 19 and gas is admitted through the ports 19 as the oscillator moves to compression position as shown at Fig. 11 so that as shown at Fig. 11 upon one side of the oscillator is a compressed charge of gas and upon the opposite side a charge of gas just introduced. The compressed charge of gas is now ignited and the oscillator is moved by the explosion to the position shown at Fig. 12 and thereby compressing the charge of gas admitted through the ports 19. This charge of gas compressed as shown at Fig. 12 is now ignited which causes the oscillator to move in the opposite direction and the valve 20 has moved through the passage 26 or in communication with the ports 18 so that the vitiated gases are exhausted through the ports 18 and passages 26 and 28 through the nozzle 29 into the turbine part of the structure. The second return of the oscillator likewise exhausts the vitiated gases through the ports 19 also into the passage 28 and through the nozzle 29 into the turbine. It will be noted, especially from Fig. 1 that the formation of the turbine increases in diameter and also in capacity as it recedes from the nozzles 29 so that the expansive forces of the gases thus exhausted are taken advantage of in operating the turbine part of the engine, finally exhausting through the chamber 31 and passage 32 without objectionable noise.

The rotation of the engine itself in the atmosphere causes a rapid cooling of the cylinder

which are exposed upon all sides to the atmosphere and thereby does away with the necessity of forced cooling of any kind either by air or water.

For the initial starting of the engine a shaft 69 is provided having a crank 70 or any other form of manual or mechanical means for applying power thereto. The shaft also carries an arm 71 having a gravity detent 72 secured thereto which engages a ratchet 73 formed in the rotating part. The detent 72 is provided with a weight 74 which when in the position shown at Fig. 4 causes the detent 72 to engage the ratchet so that a rotation of the crank 70 in the direction indicated by the arrow serves to rotate the engine. After starting the engine with the crank substantially vertical the weight 74 causes the detent 72 to leave engagement with the ratchet 73 thereby offering no impedance to the operation of the engine. The whole device is supported in any approved manner as upon the frame 75 which in Fig. 2 is shown only in section and the shape of which forms no part of the present invention.

I claim:

1. In an internal combustion engine, a plurality of cylinders mounted as a unitary structure rotating about a common axis in parallelism with the axes of the cylinders; oscillators mounted to oscillate within the cylinders; means to connect the oscillators with a stationary part to convert the oscillating motion into a rotary motion of the unitary structure; valves mounted to rotate relative to the cylinders to control the inlet and exhaust of gases to and from the cylinders; igniting elements inserted in the cylinders; rings mounted to rotate normally synchronously with the valves; means carried by the rings for exciting the igniting elements; gears carried by the valves and rings; and a manually operated controlling gear meshing with the gears of the rings. 110

2. In an internal combustion engine, a plurality of parallel, symmetrically arranged cylinders mounted as a unitary structure rotating about a common axis; moving parts within the cylinders and stationary means connected thereto; a valve for each cylinder controlling the inlet and exhaust of motive fluid to and from the cylinders, and a turbine rotating with said rotating structure and receiving motive fluid from the exhausts and through said valves. 115

3. In an internal combustion engine, a plurality of cylinders mounted to rotate as a unitary structure about a common axis; oscillators mounted to oscillate within the cylinders, means to introduce, explode and exhaust gases from the cylinders to oscillate the oscillators; a fixed shaft through the axis of said unitary structure, a disk on said shaft having a wrist pin eccentric to such 125

- axis, cranks on the shafts of the oscillators, and links connecting the cranks with said wrist pin.
4. In an internal combustion engine, a plurality of cylinders mounted as a unitary rotary structure; oscillators journaled upon the major axes of the cylinders individually; valves rotating upon the axes of the cylinders to control the inlet and exhaust of gases to and from the cylinders; igniting elements in the cylinders; rings rotating normally in unison with the valves; means carried by the rings for energizing the igniting elements; and means to manually advance and retard the energizing action of the rings.
5. In an internal combustion engine, a plurality of cylinders mounted as a unitary rotary structure; oscillators journaled upon the major axes of the cylinders individually; valves rotating upon the axes of the cylinders and adapted to control the inlet and exhaust of gases to and from the cylinders; igniting elements introduced into the cylinders; rings rotating normally in unison with the valves; means carried by the rings for energizing the igniting elements; and means to manually advance and retard the rings relative to the valves.
6. In an internal combustion engine, a plurality of cylinders mounted as a unitary structure rotating about a common axis; moving parts mounted within the cylinders; valves disposed in operative relation to the cylinders and rotating therewith and with an independent planetary movement; rings normally rotating synchronously with the valves; and manual means for advancing and retarding the rings relative to the valves.
7. In an internal combustion engine, a plurality of cylinders mounted as a unitary structure rotating about a common axis in parallelism with the axes of the cylinders; oscillators mounted to oscillate within the cylinders; means to connect the oscillators with a stationary part to convert the oscillating motion into a rotary motion of the unitary structure; valves mounted to rotate relative to the cylinders and to control the inlet and exhaust of gases to and from the cylinders; gears carried by the valves; a stationary gear controlling the rotation of the valve gears; igniting elements inserted in the cylinders; rings mounted to rotate normally synchronously with the valves; means carried by the rings for exciting the igniting elements; gears carried by the rings; and a stationary gear manually operated controlling the gears of the rings.
8. In an internal combustion engine, a plurality of cylinders mounted as a unitary structure rotating about a common axis in parallelism with the major axes of the cylinders; moving parts mounted within the cylinders; valves controlling the inlet and exhaust of motive fluid to and from the cylinders, said valves embodying passages forming communication at times between the inlet and the cylinders and other passages forming at other times communication between the cylinders and the exhaust; and a turbine rotating with said rotary structure and receiving motive fluid from the exhausts.
9. A rotary internal combustion engine comprising a stationary structure, a series of connected cylinders disposed symmetrically annularly about and parallel with the axis of said structure, oscillating pistons in each of said cylinders and connected to said structure, valve mechanism in a common plane at one end of the cylinders, and a turbine connected to said cylinders and adjacent the valve mechanism and adapted to receive exhaust gases therefrom.
10. A stationary support forming a bearing, a group of parallel cylinders symmetrically and concentrically arranged and mounted upon said support to rotate about the axis of the bearing, oscillators in said cylinders flexibly connected to said support, valve mechanism rotative about said support, and a turbine connected to said cylinders in co-axial alinement and on the discharge side of the valve mechanism.
11. In a rotary engine of the internal combustion type, a supporting structure forming a stationary journal or bearing, a plurality of parallel, symmetrically arranged and concentrically disposed cylinders mounted upon the bearing and rotative about the axis thereof, oscillators in the cylinders, connections between said oscillators and the stationary bearing, and a valve for each of the cylinders disposed at one end thereof and designed to control the admission of a gaseous fuel and the exhaust of the vitiated gases.
12. In a rotary engine of the internal combustion type, a supporting structure forming a stationary journal or bearing, a plurality of parallel, symmetrically arranged and concentrically disposed cylinders mounted upon the bearing and rotative about the axis thereof, oscillators in the cylinders, connections between said oscillators and the stationary bearing, and a valve for each of the cylinders disposed at one end thereof and designed to control the admission of a gaseous fuel and the exhaust of the vitiated gases, said valves being provided with planetary gears and adapted for relatively rotative motion to said journal structure.
13. In an internal combustion engine of the rotary type, a stationary structure forming a journal or bearing, a plurality of cylinders disposed parallel with and concentric to the axis of the bearing, symmetrically arranged with relation to each other and forming a unitary rotary structure, oscillators mounted in each of the cylinders, means at one end of the rotating structure for con-

- necting said oscillators to a relatively non-
rotary portion of the structure, and valve
mechanism at the opposite end of said cyl-
inders for controlling the induction and ex-
haust of fuel and gases to and from the
cylinders.
14. In an internal combustion engine of
the rotary type, a relatively stationary bearing
structure, a rotary structure mounted
thereon and comprising an annular series of
concentric, symmetrically arranged and par-
allel cylinders disposed about the axis of the
bearing structure, a turbine head connected
to one end of the parallel cylinders, means
for controlling the flow of exhaust gases
from the cylinders to said turbine head, and
oscillators mounted within said cylinders
and connected to a non-rotative portion of
the bearing structure at the opposite end of
the cylinders.

15. A rotary internal combustion engine,
comprising an annular series of symmetrically
arranged and parallel cylinders, a non-
rotary bearing, oscillators within the cyl-
inders having means projecting from a com-
mon end of the cylinders for connection to a

portion of the stationary bearing, a housing
for the said connecting mechanism, and a set
of rotary valves, one for each of said cyl-
inders at the opposite end thereof to the said
connecting mechanism.

16. A rotary internal combustion engine,
comprising an annular series of symmetrically
arranged and parallel cylinders, a non-
rotary bearing, oscillators within the cyl-
inders having means projecting from a com-
mon end of the cylinders for connection to
a portion of the stationary bearing, a housing
for the said connecting mechanism, a set
of rotary valves, one for each of said cyl-
inders at the opposite end thereof to the said
connecting mechanism, and a turbine in-
cluding a housing or shell portion connected
to the ends of said cylinders and substan-
tially inclosing the valve mechanism. 45

In testimony whereof I affix my signature
in presence of two witnesses.
